DESIGN FOR A MIRROR HOLDER AND THE LIKE

William Stefanakis, Astoria, Long Island, N. Y.

Application April 19, 1940, Serial No. 91,779

Term of patent 14 years

To all whom it may concern:

Be it known that I, William Stefanakis, a citizen of the United States, and resident of Astoria, Long Island, in the county of Queens and State of New York, have invented a new, original, and ornamental Design for a Mirror Holder and the like, of which the following is a specification, reference being had to the accompanying drawing, forming a part thereof, and of which Figure 1 is a view in front elevation of a mirror holder and the like showing my new design, Figs. 2 and 3 are sectional views thereof taken respectively on the lines 2—2 and 3—3 of Fig. 1, and Fig. 4 is a view thereof in rear elevation.

The characteristic features of my design reside in a mirror holder of the configuration shown having interrupted flanges arranged in relation to the openings in the main portion of the article as shown.

I claim:

The ornamental design for a mirror holder and the like, substantially as shown and described.

WILLIAM STEFANAKIS.
